(57) **CLAIM**

The ornamental design for a track lighting fixture, as shown and described herein.

DESCRIPTION

FIG. 1 is a front elevational view of a track lighting fixture showing our design;

FIG. 2 is a right side elevational view thereof;

FIG. 3 is a left side elevational view thereof;

FIG. 4 is a rear elevational view thereof;

FIG. 5 is a top plan view thereof;

FIG. 6 is a bottom plan view thereof;

FIG. 7 is a perspective view thereof, as viewed from a point above and to the left of the front of the track lighting fixture; and,

FIG. 8 is a perspective view thereof, as viewed from a point below and to the left of the front of the track lighting fixture.

The broken line showing of environmental structure in the figures is for illustrative purposes only and forms no part of the claimed design.
